UNITED STATES PATENT OFFICE.

GEORGE WESTINGHOUSE, OF PITTSBURG, PENNSYLVANIA.

GAS-PRODUCING SYSTEM.

SPECIFICATION forming part of Letters Patent No. 739,367, dated September 22, 1903.

Application filed April 10, 1900. Serial No. 12,311. (No model.)

To all whom it may concern:

Be it known that I, GEORGE WESTINGHOUSE, a citizen of the United States, and a resident of Pittsburg, in the county of Allegheny and 5 State of Pennsylvania, have invented certain new and useful Improvements in a Combined Gas-Engine and Gas-Producing System, of which the following is a specification.

My invention relates to a combined gas-engine and gas-producing system, the object of 10 the invention being to provide a highly-efficient and convenient organization of apparatus for converting the energy to be obtained from coal into mechanical power.

15 In the ordinary operation of gas-engines the products of combustion pass out to the atmosphere and the sensible heat and gaseous carbon compounds which they carry are wasted. It is usual also to cool the products 20 of combustion within the engine or as they pass therefrom by means of a water-jacket or water otherwise used; but the heat thus imparted to the water is usually wasted, the purpose being merely to cool the engine.

25 In the production of gas from coal a large quantity of heat is required, and various means have been proposed for obtaining this heat economically, and it has even been proposed to utilize a portion of the sensible heat 30 from the products of combustion of gas-engines for heating a gas-producing apparatus by causing the products of combustion to pass the atmosphere through heating-stoves, subsequently employing the heat thus stored 35 as an increment to the heat requirement of the producer.

My invention involves the utilization of a portion or all of the gaseous products of combustion themselves and the heat which they 40 carry as material and energy for the production of what is commonly known as "producer-gas." A large portion of the products of combustion from a gas-engine consists of carbon dioxide, (CO_2) and the temperature 45 at which they may pass from the engine is usually in excess of $1,000^{\circ}$ Fahrenheit. If, therefore, the hot carbon dioxide can be so acted upon as to transform it into carbon 50 monoxid, it becomes evident that an economy of great importance should result. By passing the hot products of combustion into a

suitable gas-producer containing coal I am able to convert the carbon dioxid into carbon monoxid in a very efficient manner. Not only is the sensible heat carried by the products of combustion utilized, but the carbon carried thereby, being already in a gaseous state, is all the more readily converted into producer-gas. In some cases it may be desirable to convert all of the carbon dioxid 55 carried by the products of combustion into fuel-gas, while in other instances only a portion may be thus advantageously converted. If the purpose is merely to provide sufficient fuel-gas for continuing the operation of the 60 engine itself, then it is usually sufficient if approximately one-third of the products of combustion are passed through the producer, sensible heat of the remaining two-thirds being advantageously employed for heating 65 such air as may be required and maintaining the temperature of the producer. In cases where additional gas may be required for other purposes, as in the manufacture of iron, more than one-third or all of the products of combustion may be passed through 70 the producer and the excess of gas thus obtained may be stored or utilized.

The invention will be described more in detail in connection with the accompanying 75 drawings, in which—

Figure 1 illustrates a combined gas-engine and producing system, and Figs. 2, 3, and 4 illustrate modified organizations.

Referring to the drawings, 1 represents a 80 gas-engine of any suitable character. In this instance it is shown as having three cylinders 234, organized in any well-known convenient manner for successively receiving air and gas, exploding the same, and delivering the products of combustion to the discharge-pipes 5, 6, and 7, respectively. The discharge-pipe 5 is shown as entering an air-heater 8 of any convenient form—such, for instance, as a vertical tubular heater. A suitable injector 9 is 85 provided for permitting the necessary air to be entrained with the gas, and the mixture of air and products of combustion passing downward through the tubes become highly heated and pass out through the pipe 10 and into 90 the bottom of a suitable gas-producer 11, which is represented as containing a charge

of coal. The products of combustion and the air passing upward through the coal are converted into producer-gas, which passes out through the pipe 12 into a dry coke-scrubber 5 or other suitable device for removing the tar and ash from the gas. Such a device is represented at 13. From the scrubber the gas passes through a pipe 14 to a suitable gas-cooler 15 and thence by pipe 16 to the engine 1. In practice I prefer to use in most cases a dry coke-scrubber 13 to avoid saturating the gas with moisture, and, furthermore, the tar deposited on the coke or carbon within this scrubber will be continuously gasified, thus adding the volatile hydrocarbons of the coal in a practically fixed condition to the carbon-monoxid gas. It is not, however, always necessary to use a dry scrubber, as in some instances it may be preferred to use a wet scrubber to cool the gas and to extract the moisture and the tar from the gas before it reaches the engine in any convenient well-known way.

Any convenient means may be employed 25 for regulating the amount of air supplied through the injector 9—such, for instance, as inlet-valve under the control of the engine-governor, as diagrammatically represented at 17.

30 To conserve as much of the heat as practicable, it is desirable to jacket the pipes 5, 6, 7, 10, and 18 and to provide proper means for preventing a material radiation of heat from the air-heater 8 and gas-producer 11.

35 In the arrangement shown in Fig. 1 the pipe 7 leads to the pipe 6, which enters the space around the tubes of the air-heater 8, and a pipe 18 leads from this space to an annular jacket 19 in the producer-wall, so that the 40 heat from the products of combustion from the cylinders 3 and 4 is first utilized for heating the air admitted at the injector 9, and then the remaining heat is utilized in maintaining the temperature in the producer 11. 45 From the jacket 19 the products of combustion escape to the air through a suitable flue 20.

In Fig. 2 a modification is illustrated in which the pipe 5 leads directly from the cylinder 2 to the bottom of the producer 11 instead of passing first to the air-heater 8. In this instance air is forced into and through the air-heater by means of a suitable blower 21, connected by a pipe 22 with the air-heater. The heated air passes then through the pipe 23 into the producer independently of the products of combustion. The air admitted to the blower 21 is regulated as described with reference to Fig. 1.

50 In Fig. 3 another modification is illustrated in which a suitable air-pump 24 is employed for forcing a circulation between the gas-cooler 15 and the engine, the pipe 16 leading from the gas-cooler to the pump and a pipe 65 25 leading thence to the engine. In this instance the arrangement of pipes from the en-

gine to the air-heater is similar to that shown in Fig. 2, except that the pipe 5 is shown as passing to the air-chamber of the air-heater 8, so that the air and hot products of combustion are mixed in the air-heater and pass thence through the pipe 10 to the producer 11. The positive blower 24 may serve also to compress the gas for the gas-engine in case a type of gas-engine is used in which compressed gas is desirable. Another feature is also shown in this figure consisting in utilizing the gas from the producer to prevent loss by radiation. For this purpose the produced gas passes from the top of the producer through a passage 26 into the annular chamber 19 and thence through the pipe 12 to the scrubber 13. This construction is preferable when the temperature and total amount of heat in the gas passing from the producer are greater than the temperature and amount of heat in the exhaust-gases passing from the heater 8. In this organization the exhaust-gases passing to the heater 8 through the pipe 6 escape to the air 90 from the heater through the flue 27. In Fig. 4 a modification is illustrated wherein the exhaust-gases from one or more of the three cylinders of the engine pass into the single pipe 28, leading directly to the producer 11, 95 the air-heater 8 being dispensed with. The producer in this instance is jacketed by an annular space 19, as before, and air-pipes 29 extend through this jacket-space, terminating in an annular chamber 30 near the bottom of the producer, this chamber opening into the producer through one or more passages 31. A shell or covering 32, of sheet-iron or other suitable material, arranged to guard against loss of heat by radiation, may 100 incase the producer, the air being admitted into the space 33 between the shell and the producer, and, passing upward, it enters an annular chamber 34 at the top of the producer, in which chamber the pipes 29 terminate. The air thus passing upward through the space 33 takes up the radiated heat and then passing downward through the pipes 29 becomes highly heated before it passes out from the chamber 30 into the producer through 115 the passages 31. In the drawings I have shown the producer as having the passage 26, as in Fig. 3; but the method of jacketing described in connection with Figs. 1 and 2 may be employed, if desired. The arrangement of jacketing, however, wherein the gases from the producer pass through the jacket 19, has the advantage, usually, that any slight leakage of air from the pipes 29 will produce no harmful results.

120 The arrangement described in connection with Fig. 4 in some cases results in the production of a greater amount of gas than that which is required by the engine itself, and this excess may be utilized for any desired 130 purpose, either locally at the time it is being produced or it may be stored in a holder

35 or any other desired apparatus. It appears that thirty per cent. of the exhaust-gas of an engine with a proper proportion of air passing through the producer will restore the 5 original volume consumed in the engine, so that where it is desired to produce only as much gas as is required for operating a three-cylinder engine it is only necessary that the exhaust-gases from one cylinder should be

10 passed to the producer. In the case of a two-cylinder engine or an engine having any other number of cylinders an appropriate portion of the total products of combustion may be thus utilized.

15 It will be seen that the quantity of exhaust will depend upon the load of the engine; so will the quantity of gas produced vary in like manner, the apparatus as organized becoming self-regulating.

20 For the purpose of steadyng the supply of gas to the engine a suitable holder 36 may in some instances be included in the system—as, for instance, in the pipe 16. It will be understood that instead of using air for supporting 25 the combustion within the producer oxygen in a more or less pure state may be employed.

In the drawings I have shown a common form of producer and illustrated methods of heating air. My invention is useful, how- 30 ever, in connection with any well-known form of producer, while heaters of the regenerative character may be utilized for raising the temperature of the air used in the producer. The saving of loss by radiation or the utilization 35 of radiated heat within the producer is important, and therefore by covering the pipes with an appropriate non-conducting material and in addition thereto surrounding the same with air-jackets, the current of air passing 40 therethrough entering at the point of lowest temperature and passing to the points of highest temperature and greatest radiation of heat into the producer, is within the scope of my present invention.

45 I claim as my invention—

1. The combination with a gas-engine, of a gas-producer, means for passing a portion of the exhaust-gases from the gas-engine into and through a jacket surrounding the pro-

ducer, and means for forcing a portion of 50 such exhaust-gases into and through the producer.

2. The combination with a gas-engine, of a gas-producer, means for heating air by a portion of the exhaust-gases from the gas-en- 55 gine, and means for independently passing a portion of the exhaust-gases into the producer.

3. The combination of a gas-engine having two or more cylinders, a gas-producer, means 60 for supplying the exhaust-gases from one cylinder of the engine to the gas-producer for the production of gas for operating the gas-engine and means for conserving a portion of the sensible heat of the exhaust-gases from 65 the other cylinder or cylinders.

4. The combination of a gas-engine, a gas-producer, means for passing more or less of the hot products of combustion from the gas-engine into the gas-producer for the conver- 70 sion thereof into combustible gas, an air-heating jacket for the producer and means for passing air through the jacket to the producer.

5. The combination of a gas-engine, a gas- 75 producer, means for passing more or less of the hot products of combustion from the gas-engine into the gas-producer for the conver- sion thereof into combustible gas, an air- 80 heating jacket for the producer, a connection from the producer to the gas-engine and means for establishing a circulation through the gas engine and producer.

6. A producer for converting hot products of combustion, air and coal into combustible 85 gas consisting of a producer-chamber, an inlet for the hot products of combustion, a jacket surrounding the producer-chamber, and air-passages therethrough for passing heated air into the producer. 90

Signed at New York, in the county of New York and State of New York, this 4th day of April, A. D. 1900.
